[57] CLAIM

The ornamental design for a floor lamp, as shown and
described.

DESCRIPTION

FIG. 1 is a front view of a torchere lamp embodiment of the
present invention;

FIG. 2 is a top view of the torchere lamp embodiment of
FIG. 1;

FIG. 3 is a bottom view of the torchere lamp embodiment of
FIG. 1;

FIG. 4 is a front view of a shade lamp configuration of the
present invention; and,

FIG. 5 is a top view of the shade lamp embodiment of FIG.
4.

The floor lamp is symmetrical about the vertical axis and
therefore the side and back views are identical to the front
view. The bottom view of both embodiments is identical.
